UNITED STATES PATENT OFFICE.

EDWARD G. SHORTT, OF CARTHAGE, NEW YORK, ASSIGNOR TO INTERNATIONAL AIR BRAKE COMPANY, OF JERSEY CITY, NEW JERSEY, A CORPORATION OF NEW JERSEY.

EQUILIBRIO INTERCEPTING-VALVE FOR AIR-BRAKE CONTROL.

SPECIFICATION forming part of Letters Patent No. 758,285, dated April 26, 1904.

Application filed July 1, 1902. Serial No. 113,905. (No model.)

To all whom it may concern:

Be it known that I, EDWARD G. SHORTT, a citizen of the United States of America, and a resident of Carthage, county of Jefferson, 5 and State of New York, have invented certain new and useful Improvements in Equilibrio Intercepting-Valve Mechanism for Air-Brake Control, of which the following is a specification.

10 My present invention concerns air-brakes for use with railway-trains, and relates more particularly to an equilibrio intercepting-valve mechanism which is operated by a reduction or increase of pressure-disturbing equilibrium, whereby air-brake control may be insured under varying conditions, as hereinafter set forth.

15 The main object of the improvements is to enable the release of a greater or less amount 20 of braking pressure from the brake-cylinder to be effected when brakes are set, thus obviating the necessity of going to full release.

25 Another object among many that might be mentioned is to permit a continuous and uninterrupted feed of air to the auxiliary reservoir with the engineer's valve in running position while the brakes are set.

30 The invention consists, essentially, in an equilibrium intercepting graduating-valve arranged between the triple valve and the auxiliary reservoir and controlling the outlet of the exhaust from brake-cylinder to atmosphere, said valve being in the nature of a supplemental attachment to the customary essential parts

35 of an air-brake system and being placed between two opposing pressures, one that of train-pipe air and the other that of air in the auxiliary reservoir, or in some other storage of air to which there is a steady feed, and the 40 said valve being subject to move under the fluctuations of these pressures, so as to allow more or less of the braking pressure to pass out of the brake-cylinder into the atmosphere in accordance with the necessary or desirable 45 conditions to be established in successful and efficient brake-service. It must be understood, moreover, that the present invention

supersedes and displaces the common device known as a "retaining-valve," for a retaining-valve is limited in efficiency and is set to a 50 predetermined pressure, which the engineer cannot change at will, whereas with the present improvement the efficiency may be increased at will from zero to the highest pressure necessary for braking purposes, and also 55 my present improvement takes the place and performs the duty of straight air in brake practice, affording quick release at any time with a single line of pipe and at the same time maintaining quick and automatic action; and 60 the invention consists, furthermore, in manifold details and peculiarities of construction, combination, and arrangement, substantially as will be hereinafter described and then more fully pointed out in the claims. 65

In the annexed drawings, illustrating my invention, Figure 1 is a side elevation of my improved intercepting-valve for air-brake control shown in its practical operative position in relation to the triple valve and auxiliary 70 reservoir. Fig. 2 is a vertical sectional view of my improved intercepting-valve, the same being shown as closed against its seat. Fig. 3 is a vertical sectional view showing the valve open. Fig. 4 is a transverse cross-sectional 75 view. Fig. 5 is a detail horizontal section of the cock in the pipe leading to the auxiliary reservoir or other air-storage.

Similar characters of reference designate like parts throughout the different figures of 80 the drawings.

A denotes the auxiliary reservoir, and B the triple valve, of an air-brake system.

C designates the coupling of the train-pipe to the triple-valve body. The lower part, 85 commonly termed the "drip-cup" casting, of said triple-valve body is provided with an opening at b, around which is a flange 25, to which one of the flanges of casting 1 is bolted. Within the opening b is a sleeve or bushing 10, of composition or some other suitable material, and within this bushing 10 the piston 6 is located and has a certain limited amount 90 of play. Piston 6 is secured to a flexible or

elastic diaphragm 7 by means of a clamping-nut 11, applied to the screw-threaded end of the stem of piston 6, which stem has parts 24 and 12 differing in diameter, the one 24, nearer 5 to the diaphragm 7 and on the side thereof opposite to the nut 11 being the larger.

1 designates a hollow casting having external flanges 26 and 27, whose outer faces are parallel to each other and having also a central transverse integral partition 2, formed with a central screw-threaded passage 30, containing a screw-threaded cylindrical seat-piece 3, screwed therein. The flange 26 of casting 1 is secured by bolts 28 to the valve-body flange 15 25, and the diaphragm 7, affixed to piston 6, is clamped between these two flanges. The flange 27 of casting 1 is secured by bolts 29 to a cap 4. Another flexible diaphragm 9 is clamped between the cap 4 and flange 27. 20 This diaphragm 9 is similar to diaphragm 7 and is secured to a piston 8, working in a sleeve or bushing 10 in cap 4, similar to the sleeve or bushing 10 within the opening b of the valve-body, said piston 8 being like in 25 shape, size, and other respects to its counterpart 6 at the other side of casting 1.

The cap 4 has a tubular extension 5, to which a pipe 31 is coupled by means of the union 16. This pipe 31 leads to the auxiliary 30 reservoir A or some other storage or receptacle containing air. Piston 8 is provided with a stem or rod 13, lying within the cap extension 5 and surrounded by a spiral spring 14, which is tensioned between the piston 8 35 and the flanged end of a sleeve 15, located firmly in the end of the tubular extension 5 and entered by the winged end of stem or rod 13. Piston 8 is provided also with a screw-threaded projection 32, which passes centrally 40 through the diaphragm 9 and engages the block 23, constituting the valve proper, the same having a movement toward and away from the seat-piece 3. Said valve 23 is faced with flexible material 33, as shown, and has 45 attached to its center a valve-rod 17, the end of which abuts loosely against the end of the part 12 of the piston-rod belonging to piston 6.

Running from the exhaust-port of the triple valve B to the casting 1 and entering the latter 50 at some suitable point is a pipe 18. This pipe 18 receives the exhaust from the brake-cylinder and transmits it to the intercepting-valve, whence it passes to the atmosphere. The transverse partition 2 in the intercepting-valve 55 casting 1 has a port 19 leading from the pipe 18 and emptying into an annular passage 20 in the seat-piece 3, the end of which annular passage 20 is opened or closed by means of the valve 23, of which I have just spoken. In 60 the pipe 31, that runs from the intercepting-valve to the auxiliary reservoir, is a cock 34, having an operating-handle 35. Said cock is shown in vertical section in Fig. 1 and in horizontal section in Fig. 5. By means of it the 65 passage between the intercepting-valve and

auxiliary reservoir may be closed or opened, and accordingly this cock may be used to cut out the intercepting-valve when desired.

There may be a form of the invention in which the reservoir connection 31 will be entirely omitted, in which case the spring 14 must be heavy, very much stronger than ordinary, for it will have to substitute for the combined action of the spring and reservoir pressure in the other construction, and consequently must have considerable strength and resisting power.

It will be observed from the foregoing that the intercepting-valve is balanced between two opposing pressures, one that of train-pipe air in the train-pipe space of the triple-valve body, which applies its power to the piston 6 and diaphragm 7, the other the force of the auxiliary reservoir or other stored pressure, which reaches the piston 8 through the connection 31, to which air-pressure is added that of the spring 14, which in ordinary circumstances may be comparatively light, not to exceed, say, three or four pounds. Inasmuch as the two stems or rods 12 and 17 belonging to 90 the diaphragm-provided pistons are normally in contact with each other it will be understood that if the train-pipe pressure exceeds the auxiliary-reservoir pressure the pistons 6 and 8 will be moved toward the right and the valve 95 23 lifted from its seat; but so long as the auxiliary-reservoir pressure is equal to or greater than the train-pipe pressure the valve 23 will be kept on its seat, and the escape of air from the brake-cylinder through the intercepting-valve will be prevented. Whenever the valve 100 23 is opened in consequence of the increase or the raising of the pressure against piston 6 above the counteracting pressure on piston 8, this open condition of the valve will only continue until an equalization of pressures on the two pistons has been re-established, after which the valve will of course close, it being remembered that the spring 14 supplies the slight additional amount needed to effect closing 105 110 after an equalization of pressures takes place on the two diaphragm-provided pistons.

My improved equilibrio intercepting-valve, which intercepts the discharge of braking pressure to atmosphere, except in such quantities as may be necessary, thus measuring the discharge to the needs of the case, is applicable to any one of the numerous common and well-known air-brake systems in use on railroads at the present day, especially any system employing an arrangement of triple valve, auxiliary reservoir, and brake-cylinder of the kind generally denominated the "Westinghouse" type, and in applying my intercepting-valve to any one of these systems it is unnecessary to make any change in the construction of the triple valve, the auxiliary reservoir, or the brake-cylinder further than to provide an opening in the drip-cup casting to which the casing of the intercepting-valve 115 120 125 130

may be attached. With a valve of this kind the release of air from the brake-cylinder while the brakes are set may be graduated to any desired amount, for it is not necessary that all the air in the brake-cylinder should be discharged to the atmosphere in order to reduce braking pressure to the right degree. If in order to effect release the air in the train-pipe be raised as to its degree of pressure to a point which enables the pressure against piston 6 to overbalance the pressure against its counterpart piston 8 and the valve 23, pressure will discharge out of the brake-cylinder through the triple-valve ports and passages, the pipe 18, port 19, and annular port 20, past the valve 23 and out to atmosphere through the lateral opening 36 in casting 1, and such outflow will continue until the pressures of air against the pistons 6 and 8 equalize, which will occur speedily or in a time proportionate to the amount to which the train-pipe pressure has been raised for the purpose of effecting release, but of course as soon as this complete balancing of the pressures has been restored the valve 23 will close under the influence of spring 14 and no more air from the brake-cylinder can pass at this time through the eduction-passage 20. If it is desired to release the brakes only a slight degree, the pressure in the train-pipe will be raised just a few pounds, after which equalization will take place almost immediately, and the pressure taken off the brake and allowed to escape through valve 23 while it is momentarily open will of course be comparatively insignificant, though sufficient for the immediate requirements. Furthermore, it must be remembered and borne particularly in mind as of paramount importance in the present improvements that there is a continuous feed of air to the auxiliary reservoir while the engineer's valve is in running position and while the brakes are set. This is made possible by the presence and assistance of the intercepting-valve, which prevents the escape of braking pressure to the atmosphere, except when there is a superabundance of pressure on the train-pipe side of said valve.

With my intercepting-valve the pressure in the train-pipe will be kept up to seventy pounds or thereabout at all times, and the pressure in the auxiliary reservoir will be the same, for as fast as the air is fed into the train-pipe it will pass through the feed-groove without interruption to the auxiliary reservoir, and the brakes will remain set, because until train-pipe pressure against one side of the intercepting-valve rises to a point in excess of that against the other side thereof the brake-cylinder-release action of the intercepting-valve will not occur, so that with this mechanism plenty of air is always insured for all emergency cases and every other condition of brake-service. The leakage in the train-pipe, which always takes place to a considerable

degree and is a most injurious factor in air-brake service, is effectually guarded against by this valve, for the loss by leakage is readily supplied and made good by the continuous feed resulting from the use of this intercepting-valve. 70

Ordinarily a braking pressure of fifty pounds or thereabout is the highest employed in the brake-cylinder for purposes of graduation. If a higher pressure should be generated therein, it would result in such an accumulation of power as would cause sliding or skidding of the wheels of the cars, and this would be very objectionable, and, further, it would, without the provision made in seat of valve, cause an unequal charging of the cylinders were this valve applied on only part of the cars. Hence it is necessary to provide some automatically-operating means which will furnish an outlet at the proper time when the braking pressure in the brake-cylinder has attained a safe maximum—that is to say, when it is about fifty pounds. Accordingly I construct the annular passage 20 of such size that when there is a fifty-pound pressure in the brake-cylinder acting through said passage and against the valve the valve will automatically open and allow the escape of pressure to atmosphere, it being furthermore borne in mind that the area of the valve and the strength of the spring are properly proportioned to insure this result. I am speaking now of course of graduation action, because at time of emergency the valve area need not be considered, as full pressure is applied to the brake-piston, the slide-valve at that time controlling the brake-cylinder exhaust. 85 90 95 100

When my present improved valve mechanism is attached to a Westinghouse brake or other brakes of that type, the same would be transformed into an equilibrio air-brake system. 105

Many changes in the exact construction, relative size, and precise arrangement of the parts may be made without exceeding the scope of the invention as portrayed herein and more fully described in the claims. 110

Having thus described my invention, what I claim as new, and desire to secure by Letters Patent, is— 115

1. In a fluid-pressure brake mechanism, an intercepting-valve for controlling the discharge of brake-pressure from the brake-cylinder, which valve is placed between two opposing pressures in the air-brake system and which provides that the release of braking pressure may be graduated to the needs of the case, and also that a running feed to the auxiliary reservoir may be had while the engineer's valve is in running position and brakes are set, said intercepting-valve being combined with pistons on opposite sides thereof, which have rods whose ends loosely engage each other. 120 125

2. In a fluid-pressure brake mechanism, the 130

combination with the essential elements of the system, of an intercepting-valve controlling the outlet from the brake-cylinder and situated between the train-pipe or triple valve and the auxiliary reservoir so that it may be acted on by the train-pipe and auxiliary reservoir pressures, the object of the valve being to provide for the graduating release of braking pressure, and also an uninterrupted feed to reservoir while brakes are set, said intercepting-valve being combined with pistons on opposite sides thereof, which have rods whose ends loosely engage each other.

3. In a fluid-pressure brake mechanism, the combination with the essential elements of the system, of an intercepting-valve and its casing, a brake-cylinder discharge-passage entering said casing, which passage is controlled by the intercepting-valve, pistons arranged on opposite sides of said valve, and flexible diaphragms attached to said pistons, said diaphragm - provided pistons being placed between train-pipe pressure and auxiliary-reservoir pressure to which they are respectively exposed, in order that the variation in degree of the train-pipe pressure may control the opening and closing of the intercepting-valve and thus insure graduating release and permit a running feed to auxiliary reservoir with engineer's valve in running position and brakes set.

4. In a fluid-pressure brake mechanism, the combination with the essential elements of the system, of an intercepting-valve controlling the outlet from the brake-cylinder, pistons located on opposite sides of said valve, combined therewith in such a manner that their fluctuations will open and close the valve, said pistons being in equilibrium between opposing pressures, together with a spring device for normally keeping the valve seated.

5. In a fluid-pressure brake mechanism, a controlling-valve for regulating the quantity of the discharge of braking pressure from the brake-cylinder, pistons located on opposite sides of the valve and respectively exposed to train-pipe and reservoir pressure, the variation of which will cause the valve to open, flexible diaphragms attached to said pistons; and a spring device for normally effecting the closing of the valve when the pressures are in equilibrium.

6. In a fluid-pressure brake mechanism, the combination with the train-pipe, triple valve, brake-cylinder and auxiliary reservoir, of an

intercepting-valve for controlling the discharge from the brake-cylinder, diaphragm-provided pistons located on opposite sides of this valve and having stems in endwise contact with each other and regulating the seating and unseating of the valve, one being exposed to train-pipe pressure and the other to auxiliary-reservoir pressure, all arranged and combined to allow an opening of the valve when the pressure on one side exceeds that on the other, and a closing thereof when the pressures are in equilibrium, together with a spring for the valve.

7. The combination with the essential elements of a fluid-pressure brake mechanism, of an intercepting-valve and its casing, a brake-cylinder discharge-passage entering said casing, pistons arranged on opposite sides of the valve, said pistons having rods in endwise contact with each other, diaphragms attached to the pistons and fixedly supported at the ends of the valve-casing, means for applying train-pipe pressure to one of the pistons and auxiliary-reservoir pressure to the other pistons, and a closing-spring for the valve, all combined and arranged to permit of graduating the discharge of braking pressure at the time of release, and also to permit a continuous feed to auxiliary reservoir while brakes are set.

8. In a fluid-pressure brake mechanism, the combination with the essential elements of the system, of an intercepting-valve controlling the outlet from the brake-cylinder, pistons located on the opposite sides of said valve, cylindrical guides for said pistons, diaphragms attached to the pistons and fixedly supported, stems or rods connected to the diaphragm-provided pistons, said rods being normally in contact loosely with each other and arranged so that if the train-pipe pressure exceeds the auxiliary-reservoir pressure the pistons will be so moved that the valve will be lifted from its seat, but so long as the auxiliary-reservoir pressure is equal to or greater than the train-pipe pressure, the valve will be kept on its seat and the escape of air from the brake-cylinder through the intercepting-valve will be prevented.

Signed at Carthage, New York, this 18th day of June, 1902.
